UNITED STATES PATENT OFFICE.

FREDERICK E. KERN, OF ST. LOUIS, MISSOURI.

DESIGN FOR A SHAPING AND IRONING TOOL.

58,007.

Specification of Letters Patent. Patented May 24, 1921.

Application filed June 21, 1920. Serial No. 390,654. Term of patent 14 years.

To all whom it may concern:

Be it known that I, FREDERICK E. KERN, a citizen of the United States of America, residing in St. Louis, in the State of Missouri, have invented a new, original, and ornamental Design for Shaping and Ironing Tools for Millinery Purposes, of which the following is a specification, reference being had to the accompanying drawing, forming a part thereof, in which—

Figure 1 is a front side elevation of my improved shaping and ironing tool and Fig. 2 is an end view of the tool.

I claim:

The ornamental design for a shaping and ironing tool, as shown.

In testimony whereof, I have signed my name to this specification.

FREDERICK E. KERN.
